UNITED STATES PATENT OFFICE.

WILLIAM H. BRUNT, OF BALDWIN, ASSIGNOR TO VOIGT, WARD & CO., OF PITTSBURG, PENNSYLVANIA.

GLASS SHADE.

SPECIFICATION forming part of Letters Patent No. 281,609, dated July 17, 1883.

Application filed May 28, 1883. (No model.)

To all whom it may concern:

Be it known that I, WILLIAM H. BRUNT, a citizen of the United States, residing at Baldwin township, (Pittsburg P. O.) county of Allegheny, State of Pennsylvania, have invented or discovered a new and useful Improvement in Glass Shades; and I do hereby declare the following to be a full, clear, concise, and exact description thereof, reference being had to the accompanying drawings, making a part of this specification, in which—like letters indicating like parts—

Figure 1 is a perspective view of my improved glass shade, and Fig. 2 is a vertical sectional view of the same.

My invention relates to certain improvements in glass shades for lamps, gas-jets, and similar lights; and in general terms it consists of a shade having a rounded body portion, a flat top or upper reflecting-surface, and a central chimney or draft-tube, as hereinafter more fully described and claimed.

In the drawings, *a* represents the body portion of my improved shade, which is of general rounded form, approximating, by preference, the shape of the central zone or segment of a sphere. The lower edge of this body portion is, however, contracted or drawn in, as at *a'*, and is flanged outward at the rim *a''*, forming thereby a base for support upon the usual or any suitable shade-holder. Over the upper part of the body is a flat or nearly flat cover or top, *b*, merging at the center into an upwardly extending draft-tube or chimney, *c*. This flat or horizontal top *b* may be made of white or other opaque glass, or may be painted or otherwise coated to prevent passage therethrough of light. I prefer to secure this result and thereby adapt it for use as a reflecting-surface by etching, grinding, or otherwise roughening either its inner or outer surface, or, by preference, both its inner and outer surfaces. This may be done by any of the methods ordinarily practiced in the art. Light radiated upon this flat or horizontal top from a burner below will be reflected downward at varying angles, the greater portion passing

through the clear glass of the body *a*, and thus be effective in lighting the space below the level of the reflecting-surface. But one reflection is required in doing this, and consequently less light will pass through the reflector to the space above or be otherwise wasted than occurs where two or more reflections at nearly the same angle are required to direct the light downward. This multiplicity of reflections is characteristic of flaring or cone-shaped reflecting-surfaces, such as have ordinarily been formed on the upper part of glass shades. By making a flat or nearly flat reflecting-top, as described and shown, I secure a greater percentage and better diffusion of light than heretofore in the space below the shade, where light is ordinarily most desired and useful.

In describing the body portion *a* as of rounded form, I wish to include the various suitable and well-known forms of body, and such body may also be ornamented in the usual manner and to any desired extent. Also, the tube *c* may be etched or roughened, as illustrated, or it may be made of opaque glass or of clear glass, as may be desired, with reference to securing an ornamental appearance or for other reasons.

I claim herein as my invention—

1. A glass shade for lamps and similar uses, having a flat or nearly flat top, roughened or made opaque to form a reflecting-surface, substantially as set forth.

2. A glass shade having a rounded body, *a*, and a flat or nearly flat cover or top, *b*, substantially as set forth.

3. A glass shade having a rounded body, *a*, of clear glass, a flat or nearly flat top, *b*; of roughened or opaque glass, and a central tube, *c*, extending from such flat top, substantially as and for the purposes set forth.

In testimony whereof I have hereunto set my hand.

WILLIAM H. BRUNT.
